UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

GENERATOR AND THE GENERATION OF MULTIPLE FREQUENCIES.

Application filed December 29, 1916. Serial No. 139,530.

To all whom it may concern:

Be it known that I, BURTON W. KENDALL, a citizen of the United States, residing at New York, in the county of New York and 5 State of New York, have invented certain new and useful Improvements in Generators and the Generation of Multiple Frequencies, of which the following is a full, clear, concise, and exact description.

10 This invention relates to a method and means for the generation of multiple frequencies, and has for an object to provide a means for producing currents of a frequency or frequencies higher than a given basic frequency. The higher frequency currents may 15 be used for any suitable purpose, such as sources of carrier waves for multiplex signaling.

The higher frequency currents are obtained by distorting the wave form of the fundamental frequency and by selecting the overtones or multiple frequencies present in the distorted wave.

The distortion may be effected by means 25 of an electric discharge device which has the following characteristics that give rise to a distortion. First, equal increments in the voltage applied to the device do not produce proportional changes in its output current. 30 This gives rise to a distortion, as the input voltage is not faithfully reproduced in the output circuit. This characteristic belongs to all audions which have not been provided with special means to change this characteristic. Secondly, a further and greater distortion is obtained according to the present invention by considerably overloading the audion. This is done by applying to its 35 input terminals an alternating potential such that the maximum value carries the operation of the tube beyond that portion of its characteristic which is substantially linear, thus substantially distorting the wave form of the applied alternating potential as repeated by the tube. This applied alternating potential may be such that the maximum positive value will exceed that necessary to cause the tube to become saturated and the maximum negative value will exceed that 45 negative value required to reduce the output current substantially to zero, or one of these conditions may exist alone to the substantial exclusion of the other. The number of elec-

trons which can be given off by a thermionic cathode at a certain temperature has a limiting or saturation value and the corresponding point on the characteristic curve of the electron discharge device may be termed the saturation point of the cathode for that temperature. Accordingly the cathode will limit 55 the space current which can flow in the thermionic device and variations in the internal impedance in the circuit of the space current are not followed by proportionate changes in the value of space current. Thus the wave 60 form of the output current will be considerably distorted. Thirdly, in some cases a further distortion may be obtained in the suppression of the alternate half waves by passing the distorted wave through a unilaterally 65 conducting device, such as a thermionic rectifier. A particular electric discharge device 70 may have one, two or even three of the distorting characteristics just described.

The harmonics selected may be amplified 75 to any high power value, and purified by means of tuned circuits or filters which suppress the undesirable frequencies and selectively transmit the amplified overtone or harmonic.

80 Various systems for carrying out the invention are shown in the drawings, in which

Fig. 1 shows diagrammatically an oscillator of the audion type which is considerably overloaded to produce a distorted wave 85 form;

Fig. 2 shows a system in which a separate source of oscillations is adapted to supply a thermionic device which may be considerably overloaded;

Fig. 3 illustrates how the generating scheme of Fig. 2 may be combined with a selecting means shown in Fig. 1.

Figs. 4 and 5 are modifications in which 90 thermionic rectifiers are used.

In Fig. 1, 6 is any oscillation generator of the audion type. The generator may be of the form disclosed in the United States Patent No. 1,356,763 to Ralph V. L. Hartley, patented October 26, 1920, for Oscillation 100 generators. The generator 6 is a thermionic device of the audion type in which the output circuit is coupled to the input circuit by means of the inductively related coils 7 and 8. Space current for the oscillator 105 6 is supplied by the battery 6'. The funda-

mental frequency of the oscillations supplied by the generator 6 is determined by the adjustment of the variable condenser 9 in shunt to coils 7 and 8. Inductively related to the coils 7 and 8 is the coil 10, in circuit with which are the loop-resonant circuits A^1 , A^2 , etc., each of which is tuned to a different multiple of the fundamental frequency supplied by the generator 6. The 5 loop-resonant circuit A^1 is tuned to the first overtone, which is the second multiple frequency, and this loop-resonant circuit comprising the condenser 11 and the inductance 12, accordingly provides a path of high 10 impedance for currents of the first overtone and provides a path of low impedance to currents of different frequencies. Similarly, 15 each of the loop-resonant circuits A^2 , A^3 , etc., provides a path of low impedance to 20 currents of frequencies different from its resonant frequency, while the resonant frequencies are supplied to the out-going lines associated with the loop-resonant circuits. By means of the loop-resonant circuit 25 A^1 , the first overtone is impressed on input circuit of one or more amplifiers 13. The adjustment of a vacuum tube of the audion type for its operation as a voltage or current amplifier is described and claimed 30 in the patent to Arnold, No. 1,329,283, January 27, 1920, for Thermionic amplifier. The output circuit of the amplifier 13 is coupled by means of the transformer 14 to the filter 15 which selectively transmits 35 the amplified first overtone to the line 16. The filter 15 is described and claimed in the United States Patent to Campbell, No. 1,227,113, patented May 22, 1917, for Improvements in electric wave filters. The 40 second overtone, if desired, need not be amplified, and, accordingly, the line 17 may be directly connected to the loop-resonant circuit A^2 . The amplifier 18, associated with the loop-resonant circuit A^3 , is similar to 45 the amplifier 13 above described. The amplified third overtone in the output circuit of the amplifier 18 may be purified or selectively transmitted by means of the circuit 19, tuned to the frequency of this harmonic. The lines 16, 17, 19, etc., selectively 50 transmit the segregated harmonics to suitable translating means not shown.

In Fig. 2 the generator 20 may be a higher frequency alternator or may be an oscillator 55 of the type described in connection with Fig. 1. The generator 20 is coupled by means of transformer 21 to the input circuit of the thermionic repeater 22, the input circuit of which is tuned to the frequency supplied by the generator 20 by means of 60 the condenser 23. Space current in the output circuit of the repeater 22 is supplied by the battery 24. The output circuit of the repeater 22 is coupled by means of the transformer 25 to the line 26, bridged across

which are the tuning condensers and inductances F^1 , F^2 and F^3 , tuned to the first, second and third overtones, respectively, of the frequency supplied by the generator 20. The tuning device F provides a path for 70 currents of the fundamental frequency. By means of the coil 29, inductively related to the coil 27, forming a part of the tuning means F^1 , currents of the first overtone are transferred to the input circuit of the amplifier 28, similar to the amplifiers above described. The input circuit of amplifier 28 may be tuned to the first overtone by means of the variable condenser 29. The output circuit of the amplifier 28 is coupled by 80 means of the transformer 30 to the filter 31, which selectively transmits the amplified first overtone to the line 32. By means of circuit 37, tuned to the second overtone, currents of this frequency may be directly 85 transmitted to the line 38 without amplification or further purification if desired. The circuit associated with the tuning means F^3 , is similar to that associated with the tuning means F^1 except that instead of 90 using a filter such as 31, the tuned circuit 35 may be used.

In Fig. 3, generator 20 and the thermionic repeater 22 are connected in a manner similar to that shown in Fig. 2, while the means 95 for selecting the different harmonics from the output circuit of the repeater 22 are similar to those shown in Fig. 1.

In Fig. 4, instead of using a three-element audion tube to effect the distortion, the thermionic rectifier 36 may be used. Coupled with the rectifier 36 is the circuit arrangement for amplifying and selecting, as shown in Figs. 1 and 3.

The modification disclosed in Fig. 5 is 105 similar to that shown in Fig. 4, except that the scheme of amplifying and purifying, as shown in Fig. 2, is used.

In each of the audions shown, an electron stream is established between the heated 110 filament and the output electrode by means of the direct current source in the audion output circuit.

As to the operation of the systems disclosed in Figs. 1, 2 and 3, an alternating 115 voltage is supplied to the grid circuits of the thermionic devices 6 and 22 of such a high maximum value that for all voltage values above a given value, the output current is unresponsive thereto. This high input voltage tends to produce greater variations in the output current than are possible under the limitations (1) that current can flow in but one direction in this circuit, and (2) that the magnitude of this current is 120 limited to the number of available carriers, which depends on the operating conditions of the filament. A distortion of the wave form in the output circuit of the thermionic device results and the various harmonics 125 130

present may be selected, amplified and purified by the means shown.

In Figs. 4 and 5, the distortion is effected by suppressing alternate half-waves, as the

5 rectifiers 36 are essentially unilaterally conducting, and further distortion may be secured by overloading. In this case also the harmonics present may be segregated, amplified and purified.

10 In the figures, three different circuit arrangements have been shown for picking off certain harmonics, but it is obvious that any one of these arrangements may be used to select any one of the harmonics.

15 What is claimed is:

1. The method of obtaining frequency harmonics of a base frequency comprising overloading a thermionic device.

20 2. The method of obtaining frequency harmonics of a base frequency comprising overloading an electric discharge device.

3. The method of obtaining frequency harmonics of a base frequency comprising overloading a vacuum electric device.

25 4. The method of harmonic generation which consists in overloading a thermionic device and selecting a harmonic component from the resulting distorted wave form.

5. The method of harmonic generation 30 which consists in generating a non-sinusoidal wave form distorting said wave form, selecting a harmonic component thereof, and purifying said component.

35 6. The method of harmonic generation which consists in generating a non-sinusoidal wave form, distorting said wave form, selecting a harmonic component thereof, and selectively transmitting said component.

40 7. An arrangement for obtaining frequency harmonics of a base-frequency wave comprising an electric discharge device having coupled input and output circuits and means for continuously overloading said device whereby an electromotive force of the 45 base frequency applied to said input circuit is repeated to said output circuit as a distorted wave comprising the desired harmonics.

50 8. An arrangement for obtaining frequency harmonics of a base-frequency wave comprising a three-element electric discharge device having coupled input and output circuits and means for continuously overloading said device whereby a wave of 55 the base frequency impressed upon said input circuit is repeated to said output circuit as a distorted wave comprising the desired harmonics.

60 9. The method of alternating current production which comprises establishing an electron stream from a source of electrons operating in the region of its saturation point and periodically varying the impedance presented to said electron stream.

65 10. A series circuit including a source of

current, means for limiting the value of the current flowing in said circuit and a variable impedance, and means for periodically varying the value of said impedance.

11. A generator of distorted wave forms 70 comprising a thermionic device having an electron emitting cathode arranged to operate in the region of its saturation point, an input circuit connected to said cathode, and an output circuit coupled to said input circuit. 75

12. In combination, a generator of non-sinusoidal waves of a base frequency and a circuit comprising a wave form distorting device connected thereto, said circuit also 80 comprising means for selecting harmonics of the base frequency.

13. An electric system comprising a thermionic device of the vacuum tube type having an input circuit and an output circuit 85 coupled to said input circuit, a source of current for said output circuit, and means for overloading said device by supplying to said input circuit alternating potential of such high value that the current in the said 90 output circuit is substantially unresponsive to an increase in said potential beyond a given value.

14. A harmonic generating system comprising a thermionic device of the vacuum 95 tube type having an input circuit and an output circuit, a source of current for said output circuit, a source of alternating potential for said input circuit, and means associated with said output circuit for isolating 100 a periodic component of the output current having a frequency harmonic to that of the potential supplied to said input circuit.

15. A harmonic generating system comprising a thermionic device of the vacuum 105 tube type having an input circuit and an output circuit, a source of current for said output circuit, means for supplying an alternating potential to said input circuit and means associated with said output circuit for 110 isolating a periodic component of the output current having a frequency harmonic to that of the potential supplied to said input circuit.

16. A harmonic generating system comprising a thermionic device of the vacuum 115 tube type having an input circuit and an output circuit, a source of current for said output circuit, a source of alternating potential for said input circuit, means associated with said output circuit for selectively transmitting a periodic component of the output 120 current having a frequency harmonic to that of the alternating potential supplied to said input circuit and means for amplifying said 125 component.

17. A harmonic generating system comprising a thermionic device of the vacuum tube type having an input circuit and an output circuit, a source of current for said 130

output circuit, means for supplying an alternating potential to said input circuit, means associated with said output circuit for selectively transmitting a periodic component of 5 the output current having a frequency harmonic to that of the potential supplied to said input circuit and means for amplifying said component.

18. In a harmonic generating system, the 10 combination of a thermionic device of the audion type having an input circuit and an output circuit, a source of fundamental frequency alternating potential for said input circuit, means for tuning said input circuit

to the frequency of said source, a source of 15 current for said output circuit, means for selecting a harmonic frequency from said output circuit, a thermionic amplifier having an input circuit and an output circuit, means for supplying said amplifier input 20 circuit from said selecting means, and means for purifying the amplified harmonic frequency supplied by said amplifier.

In witness whereof, I hereunto subscribe my name this 28th day of December, A. D. 1916.

BURTON W. KENDALL.
